UNITED STATES PATENT OFFICE.

JOHN GOOD, OF GARDEN CITY, NEW YORK, ASSIGNOR TO GOOD INVENTIONS CO., OF NEW YORK, N. Y., A CORPORATION OF NEW YORK.

ENGINE-HEATING APPARATUS.

Application filed May 21, 1923, Serial No 640,618. Renewed November 21, 1927.

The invention relates to apparatus for furnishing hot vaporized mixture of liquid fuel and air to internal combustion engines either for the purpose of setting them in 5 operation on low grade fuel or when cold, or for assisting in their operation after starting and during the warming up period, or both, and so as to enable such engines, and particularly automotive engines, to be 10 used with greater facility on low grade fuels than heretofore possible. The invention consists in the improved arrangements for producing and supplying such hot combustible mixture, as hereinafter described and as 15 illustrated in the accompanying drawings, and in various combinations and sub-combinations thereof, which will be apparent to those skilled in this art.

The accompanying drawings illustrate the 20 principle of the invention in several forms and for convenience of illustration show the apparatus partly in diagrammatic arrangement; it will be understood that the physical shape of the principal parts and their 25 relative arrangement depend on the design of the engine on which they are used and that in practice they are built in compact and closely assembled relation, sometimes 30 in the nature of an attachment to existing engines as herein shown and sometimes they are built into the engine carburetor.

In said drawings, Figure 1 represents a conventional automotive engine having one form of the invention applied to it; Figure 35 2 is an enlarged section of the means for supplying the hot medium of Figure 1; Figure 3 a smaller section of the burner and auxiliary fuel supply of a modified form; Figure 4 details of the safety burner vent; Figure 5 represents a conventional automotive engine having a different form of the invention applied to it; Figure 6 a longitudinal section of the auxiliary fuel supply and burner thereof.

45 Referring first to the form shown in Figs. 1 and 2, the engine is supplied with a hot vaporized mixture of fuel and air through a passage 1 which may be connected to the suction intake passageway 2 in a variety of ways, either above or below the carburetor 3 as preferred but is herein shown as connected above the throttle 4 and by means of an adapter fitting 5 which may be interposed between the attachment flange of the 50 carburetor and that of the suction manifold.

It will be understood that the carburetor 3 is associated with the usual constant level or float chamber which is supplied with liquid fuel from any appropriate source and that its throttle 4 is to be connected by appropriate linkage to a suitable throttle lever or pedal at the operator's station for control of the engine in the usual way. It is preferred to use the form of the invention under description in connection with an intake manifold which is associated with the exhaust manifold 7 in such a way as to supply such heat as may be necessary to perfect the engine charge mixture after the engine is under way, so that the heating 70 arrangements about to be described will require to be kept in operation only for the initial period or on special occasions.

The passage 1 is connected to or forms part of a device constituting a source of mixture of fuel and air which is here termed an auxiliary carburetor, inasmuch as its function is to create and maintain a mixture of liquid fuel and air in proportions which are substantially constant or at least predetermined. It operates by the effect of the suction present in the engine intake when the engine is being turned over by the starter mechanism or is operating by virtue of its own combustion cycle. In the present case, 85 and as shown in Fig. 2, this auxiliary carburetor comprises a fuel well 8 connected by a pipe or duct 9 with the fuel bowl 6 of the main carburetor and at about the same elevation so that the fuel level therein will occupy substantially the same position as in the carburetor fuel bowl. The tube 10, connected through its spiral convolutions 11 with the passage 1, dips into this fuel well and is adapted to suck up liquid therefrom 90 through its restricted submerged opening 12. The liquid so sucked in passes through the small interior tube 13 into the upper part of the tube 10 and is there mixed with air drawn in through the holes 14, thus producing a mixture of fuel liquid and air for passage through the convolutions 11 and the pipe connection 1 to the engine intake. The small hole 15 connects the space above the liquid level in the closed end of the tube 10 95 with atmosphere, so that when suction is first transmitted to the tube the effect is to deliver, initially, a relatively large amount of liquid fuel through the tube 13 until the level drops to a point where it will be maintained 100 105 110

by the inflow through the restricted opening 12, whereupon the rate of delivery of fuel by the tube 13 becomes constant or substantially so. The opening 12 may be adjustable. 5 The principle of operation of this auxiliary carburetor is not different from that of many carburetors known to the art, on which account the general arrangement has been only diagrammatically shown in the drawing. It 10 is desirable, though not strictly necessary, that the auxiliary carburetor of this invention shall deliver a mixture extra rich in fuel when it begins to operate, because this is found useful in practice for a number of reasons, especially when the engine is very cold. The communication of this auxiliary carburetor with the intake passage is preferably put under the control of the operator as by means of a valve of some sort which 15 may be in the passage 1 or elsewhere. The valve marked 15 has been devised as capable of satisfactory operation and great durability notwithstanding the presence of a considerable degree of heat in the medium passing it. This valve consists of the valve proper 15, of the poppet type loosely mounted by its stem in a sliding plunger block 16 by which it can be advanced into engagement with the seat 17, thus shutting 20 off the connection between the engine and the auxiliary carburetor. The sliding block 16 is connected by a flexible wire 18 housed in a tube 19 to a button 20 mounted on the instrument board of the vehicle and a spring- 25 pressed ball or other detent 21 is applied to the block 16 or to some part moving with it, to hold the valve in its closed position so that it is not likely to be opened, when not desired, as by the effect of a back-fire in the 30 intake passage. This form of valve is particularly useful in controlling the flow of hot media and is claimed in a companion 35 application.

The source of heat, associated with the auxiliary carburetor for the purpose of producing the hot vaporized mixture above referred to, consists in the present case of a liquid fuel burner supplied with fuel and combustion air by the act of the operator, 40 either manually or otherwise, and comprising an ignition and mixing space arranged to heat the convolutions of the tube 11 above referred to. Liquid fuel is admitted to this space by the pipe or duct 22 from the fuel 45 well 8 above referred to and by virtue of the aspirating effect of an air jet 23 supplied with fluid pressure by a hand air pump 24 mounted on the instrument board at the operator's station. This pump 24 is operated by reciprocating the plunger therein and may be of any appropriate design for this purpose, or its function may be substituted by other styles of pump,—power-driven if desired. The chamber 25 constitutes an 50 accumulative reservoir, or air dome, adapted

to absorb the pump plunger fluctuations, so that the air jet at 23 will be fairly constant in velocity. This chamber contains the pump. By means of the pressure of the pump, a fine spray of liquid fuel is produced 55 within the burner and adjacent the gap of a spark plug 26, which ignites it. Air for supporting the combustion is admitted to the mixing space, laterally, through the combustion air entrance 27, the inward flow being 60 induced by the injector effect of a second air jet 28 connected to the air pump or pressure source, through the cross channel 29. The entrance to the combustion air passage 27 is protected by a small screen as indicated, 65 and the air inflowing therethrough combines with the ignited spray at a point somewhat beyond the point of ignition and in such a manner as to produce complete combustion 70 of all of the fuel. The flame and products 75 of the combustion pass over or between the convolutions 11 and escape through the exhaust outlet 30.

This outlet is guarded against the escape 80 of flame which might inflame the carburetor or other parts of the engine and the guarding means consists of a stack of thin, spaced, 85 annular plates 31 such as shown in perspective in Figure 4. These plates are assembled 90 concentrically to the outlet of the burner 95 casing and shrouded and concealed by a cover 32 so that the burner products must pass through the crevices between them. This suffices to extinguish any flame without 100 imposing an appreciable back pressure. The spacing of the plates is formed by crimping them in the manner indicated in Figure 4 and they and the cover 32 are all held to the burner casing by the two screws 105 33, making a very simple, cheap and also safe 110 exhaust outlet. An internal baffle plate 34 is preferably mounted at the end of the tubular coil within the burner in order to force the flame into intimate contact with the latter, but obviously the burner gases 115 can be made to give up heat to the auxiliary 120 carburetor in many other ways.

The spark plug 26, or an equivalent ignition means, is arranged to be put in operation 125 conjointly with the opening of the valve 15 or the operation of the air pump, preferably the former, and for this purpose the housing of the push button 20 is provided with an electric switch 39, which, when the button 130 is pulled out to open the valve 15, closes the primary circuit of the storage battery shown in diagram and thereby produces operation of the spark coil 35, which in turn operates the igniter 26 through the wire connection 36. In place of this circuit arrangement any other ignition system can obviously be used 135 which will suffice for the purpose.

In the operation of the engine above described and assuming the same to be ready for starting and to require heat for that purpose, 140

the operator pulls outwardly the button 20, which, in the present case, sets the igniter in operation and opens the valve 15, thereby putting the engine in communication with the auxiliary carburetor. He then pumps a few strokes on the air pump 24, which starts the burner in operation, heating the coil 11. If at the same time he cranks the engine as by means of the starting motor 37 and starting switch 38, a mixture of fuel and air from the auxiliary carburetor will be drawn through and vaporized by the hot coil, and on arrival in the engine cylinders, will fire and start the engine under its own cycle. Thereafter, the pumping may be continued if desired or necessary until sufficient heat is developed in the engine itself to continue the vaporization of the fuel. When the pumping has been discontinued, the auxiliary carburetor continues in operation without the aid of burner heat and merely contributes its mixture to that from the main carburetor, the only effect of such contribution being a somewhat higher speed of the engine during the period the auxiliary carburetor is allowed to supplement the main carburetor. This higher speed is not objectionable and is in fact desirable in many cases, but can be discontinued whenever desired as by closing the shut-off valve 15.

The modification of Figure 3 consists in the provision of an opening 40 leading from the interior of the flame space of the burner into the delivery tube of the auxiliary carburetor. This opening is for the purpose of admitting burner flame directly into contact with the auxiliary mixture for the purpose of expediting the vaporization of the liquid fuel therein; it does not inflame that mixture. The flame is drawn in by the same suction effect that operates the auxiliary carburetor. As some excess of oxygen may also be drawn in with the flame, it may be necessary in this form, to reduce somewhat the area of the holes 14, if it is desired to maintain the same proportions in the auxiliary mixture as in the other case. The rest of the burner construction will be recognized as identical with that above described.

Coming now to the form of Figs. 5 and 6, the general organization of the engine, its intake mechanism, carburetor, and the burner and its operating mechanism will all be recognized as the same as already described. The auxiliary carburetor in this case is formed by a simple tube 43 dipping into a compartment 44 having a restricted fuel inlet 12 from the well 8. The upper end of this tube constitutes the fuel jet and delivers into an air passage 45 leading through the thin walled tube 46, exposed to the flame inside the burner casing, and thence by the pipe or duct 47 to the valve controlled passage 1 already described. The air pressure jets 23

and 28 are also arranged as described in connection with the previous form, and their action is also the same, the flame and products of combustion escaping from the burner casing through a baffled outlet constructed as 73 in the previous form.

The outlet, of this burner, is provided with a gravity-seated outwardly opening check valve 48, which provides for the operation of the burner also by the suction effect of the rotating engine. For this purpose the passage connecting the auxiliary carburetor to the engine is provided with a hole or passage 49 opening directly into the ignition and mixing space of the burner. When an adequate suction is transmitted to the burner through this opening, combustion air is sucked in through the entrance 27 and liquid fuel through the tube 22. This fuel drops or flows into the small sink or well 50 in the bottom wall of the burner, in which one or several small drill holes are formed. The inflow of air through these holes creates a spray of the fuel which burns with the combustion air sucked in through entrance 27, and the flame and hot products of combustion are thence sucked through the passage 49 into contact with the mixture from the auxiliary carburetor, quickly preparing the latter for instant ignition on arrival in 90 the engine cylinders, the general effect being the same as in the form first described except that the heating is done continuously and automatically as long as the engine suction is transmitted to the burner. The mixture of the flame with the auxiliary fuel does not ignite the latter.

The proportions of this burner are such as to provide a considerable excess of combustion supporting air beyond that necessary merely for the complete consumption of the burner fuel. Such proportions are desirable as a simple means of avoiding the tendency of explosions or popping in the burner and in consequence of the use of this design of burner, which may for convenience be called an excess air burner, the mixture produced by the auxiliary carburetor is given a predetermined degree of over richness in fuel sufficient to compensate for the excess air 115 or uncombined oxygen drawn in with the flame through the passage 49, and make therewith a resultant mixture of proportions suitable for engine operation, such as may be used with the mixture from the main carburetor, or as may be used alone when the auxiliary carburetor is made of sufficient size for that purpose.

It will be apparent that when used with an excess air burner the auxiliary carburetor could if desired be reduced to the form of a simple fuel jet with no provisions for mixing air with such jet except the excess air from the burner. The resulting hot mixture could in such a case have the sameulti- 125 130

mate proportions as formerly, adapting it to be admitted to, or excluded from, mixture with the main carburetor mixture without affecting the ultimate proportions of fuel and air received by the engine cylinders.

It will be understood that the spark plug 26 has the same function in this burner as in the form first described and that it is available to light the fuel spray produced either 10 by the pressure operation of the burner or by its suction operation. In the use of the apparatus described, the ordinary cranking of the engine, as by pressing the starter button 38, may create sufficient suction in the 15 burner to result in the initiation of combustion and consequent operation in the manner above described. The pressure source represented by the pump, however, is available as a stand-by to be used in case the engine 20 suction effect is not strong enough to produce a spark-ignitable spray. In very cold weather, or with a weak starting battery, the suction effect produced in a cranked engine may be feeble and not sufficient to 25 produce ignition of low grade fuel. The pressure source 24 can, if desired, be operated prior to the cranking of the engine and may be operated coincidently therewith and subsequently thereto, and it may be used 30 either for supplying both air jets 23 and 28 or merely to supply the jet 23, in which case its function will be merely to create an ignitable fuel spray in the burner as an assistance or booster to the suction operation of 35 the latter. The pressure source in this form also, may if desired, be power driven, as by means of a small air pump and electric motor and the heat developed may be utilized for other purposes than that described. The term pressure as used herein 40 and in the claims refers to the pressure produced by the pump 24 or other pressure source, which is above atmospheric, as distinguished from the pressure difference 45 created solely by the natural suction of the engine intake.

In all of the forms of the inventions above described the heating device is arranged at substantially the same level as the carburetor fuel bowl and the fuel which is vaporized by it does not require to be lifted to any considerable elevation before it is converted into vaporous form; after vaporization it is of course easily carried upwardly to the intake header, and a very feeble cranking effect is therefore sufficient to supply the engine with fuel, which by the use of the burner is converted into an ignitable starting mixture, the result being that the apparatus enables starting to be accomplished under the most unfavorable conditions. Certain of the matter herein disclosed, but not claimed, is claimed in co-pending application Ser. No. 640,620.

Having now described the principle of the

invention and the preferred method of putting the same into effect, the following is claimed:

1. The combination, in an internal combustion engine, of a carburetor, an auxiliary carburetor and a liquid fuel combustion device associated with the latter, comprising a pressure means for spraying the fuel therein and an igniter, and adapted to cause said auxiliary carburetor to deliver a hot mixture of fuel and air.

2. The combination in an internal combustion engine, of a carburetor, an auxiliary fuel jet to supply fuel to the engine, a liquid fuel combustion device adapted to heat such auxiliary fuel, a source of operating fluid pressure for said combustion device, an igniter therefor, and means independent of said carburetor to supply air for the combustion of said auxiliary fuel.

3. The combination in an internal combustion engine of a carburetor, an auxiliary carburetor and a liquid fuel combustion device adapted to cause the latter to give a hot mixture, said device comprising an ignition and mixing space connected to a source of fluid pressure, and an outlet for venting the combustion products outside of the engine.

4. The combination in an internal combustion engine, of a carburetor, an auxiliary carburetor, and a liquid fuel combustion device comprising a source of fluid pressure arranged to spray the fuel and supply the air to burn the same and an igniter, and adapted to cause said auxiliary carburetor to produce a hot fuel and air mixture.

5. The combination in an internal combustion engine, of means for producing engine-operating fuel mixture, for combustion in the engine, a liquid fuel combustion device for supplying heat to said mixture, means for operating said device by pressure and a flame stifling outlet carried by said device adapted to vent the pressure therein to atmosphere.

6. The combination in an engine of the intake passage including a carburetor, a liquid fuel combustion device associated with and adapted to heat the intake fuel mixture and an outlet to atmosphere from said device comprising a stack of spaced plates carried by said device and forming a plurality of crevices adapted to extinguish flame.

7. The combination of an engine intake, a liquid fuel combustion device associated therewith and two outlets from said device, one of said outlets leading to said intake and the other to a point outside said intake.

8. The combination of an engine intake, a liquid fuel combustion device associated therewith and two outlets for combustion products from said device, one of said outlets leading to said intake and the other to atmosphere and means for baffling the latter outlet.

9. The combination of an engine intake, a liquid fuel combustion device associated therewith having two outlets for combustion products, one of said outlets leading to the intake and means to control the flow to the intake through said outlet.
10. The combination in an engine, of a carburetor and auxiliary carburetor, a fluid pressure operated burner associated therewith and means for admitting combustion products of said burner to the mixture of said auxiliary carburetor.
11. The combination in an automotive vehicle of the engine having a suction intake, of a liquid fuel combustion device associated therewith, and manual means at the operator's station for starting and maintaining said combustion device in operation independently of the suction in said intake.
12. The combination in an automotive vehicle of an engine having a suction intake, a liquid fuel combustion device associated with said intake and including electric ignition means, and means at the operator's station for conjointly controlling said ignition means and manually supplying fuel to said combustion device.
13. The combination in an automotive engine, of a carburetor, an auxiliary fuel jet, a combustion device associated with the latter and a hand operated air pump located at the operator's station and connected to said device.
14. The combination in an automotive engine, of a carburetor, an auxiliary carburetor, a combustion device for heating and thereby vaporizing the liquid fuel of said auxiliary carburetor, means at the operator's station for controlling the admission of fuel from said auxiliary carburetor to the engine, and other means at said station for controlling said combustion device.
15. The combination in an automotive vehicle of an engine having an intake, a liquid fuel combustion device including electric ignition means and communicating with said intake, and manually operated means at the operator's station for conjointly operating said combustion device and energizing its said ignition means.
16. In an internal combustion engine, the combination of a carburetor, a liquid fuel burner associated therewith, adapted to be operated by the suction effect of the engine and means for independently supplying a fuel spraying pressure to said burner.
17. In an internal combustion engine, the combination with the carburetor, of a liquid fuel burner having an outlet for its combustion products opening into the path through the carburetor and adapted for operation by the engine suction, and means for supplying fluid pressure to said burner for operating the same.
18. In an internal combustion engine, a carburetor, a liquid fuel burner associated therewith, means for supplying operating fluid pressure thereto and a check-valved escape for combustion products therefrom.
19. In an internal combustion engine, the combination with the intake including the carburetor, of a burner associated therewith having a connection by which suction is imparted thereto from the intake, means for supplying an operating fluid pressure to said burner and a non-return outlet leading from said burner to a point outside the intake.
20. In an internal combustion engine, the combination with the engine intake, means for producing an engine operating mixture of fuel and air, a burner associated therewith and adapted to be operated by the suction effect of said intake and fluid pressure means for operating said burner including an air jet arranged to induce an inward flow of combustion supporting air in said burner.
21. In an internal combustion engine, the combination of a main carburetor, an auxiliary carburetor and a liquid fuel burner adapted to be operated either by the suction effect of the engine or by pressure applied to it.
22. In an internal combustion engine, the combination with the suction intake including a carburetor, a suction burner connected thereto and including suction-operated fuel-spraying means, pressure means for spraying fuel in the burner and an igniter in the burner.
23. In an internal combustion engine, the combination with a suction burner, containing an igniter, pressure means to spray fuel therein, a well to receive liquid fuel in the burner and an air jet in the bottom of said well.
24. The combination of a suction intake, a suction burner having suction-operating fuel spraying and air admission means, an electric igniter and additional fuel spraying means for producing an electrically ignitable fuel mixture in said burner.
25. In a combustion engine, the combination with the intake including a carburetor, of a liquid fuel burner connected to said intake and adapted to be operated by the normal engine suction effect therein, and means independent of the engine for increasing the pressure difference by which said burner is operated.
26. In a suction burner for internal combustion engines, the combination with a body providing a combustion chamber communicating with the engine intake, of means for directing a jet of fuel into the chamber, means for collecting fuel particles from the first jet and for causing a jet of these particles to be directed toward the first jet, and means for igniting the fuel.
27. In a suction burner for internal com-

bustion engines, the combination with a burner body in communication with the engine intake, said body including a combustion chamber, of a fuel nozzle for admitting fuel spray, ignition means for said spray, and means providing a bubbler orifice located in the bottom of said body back of the ignition means for mixing air with fuel tending to collect in the bottom of the burner.

28. In a suction burner for an internal combustion engine having an intake, the

combination with a burner body in communication with the engine intake, said body including a combustion chamber, of a fuel duct connected with the combustion chamber, said body being provided with a bubbler orifice through the bottom thereof for mixing air with fuel tending to collect in the bottom of the burner.

20 In testimony whereof, I have signed this specification.

JOHN GOOD.
